UNITED STATES PATENT OFFICE

MASA NAGAO, OF TOKYO, JAPAN, ASSIGNOR TO YUKA YASHIMA, OF TOKYO, JAPAN

HYDRAULIC ACCOMMODATION FAN

Application filed July 15, 1927, Serial No. 206,087, and in Japan August 22, 1926.

This invention relates to improvements in or relating to a hydraulic fan and has for its object to provide a new accommodation fan by which a cool and refreshing draft of air ⁵ can be supplied during a long and continuous use of the fan.

In the accompanying drawings:

Fig. 1 is a vertical sectional view of the new fan partly in elevation showing the inner construction thereof,

Fig. 2 is a partial sectional view along the line A—A of Fig. 1.

In the drawings, there is provided a hollow stand 1, the top of which forms a casing for a turbine rotor 2. A common shaft 3 is provided for said rotor 2 and also for fan blades 4. A fan guard 5 is fitted to the top of the hollow stand while a frame 6 is also fitted to the top of the hollow stand at one side thereof opposite to the vanes. The shaft 3 is supported by the pointed ends of screw studs 7 and 8 respectively adjustably mounted in the central solid part of the guard 5 and in said frame 6 as shown, the ends of the shaft 3 being provided with conical axial recesses 9 and 10 for the purpose of receiving said pointed ends. The rotor 2 is provided with a row of angle shaped blades 11 at the middle of the periphery thereof and two rows of arc shaped blades 12, one at each side of the middle blades 11, the middle and the side blades forming two series of turbine blades of reaction type in directions from the middle of the periphery to both sides of the rotor. A tube 13 is provided for supplying pressure water, the top end 14 of which forms a water nozzle at the center of said middle blades to divide the supply of pressure water to said two series of the water blades. The shaft 3 is also provided with discs 17 and 18 for preventing water from splashing and leaking out of shaft holes 15 and 16 in the side plates of the casing at the top of said hollow stand 1. These discs 17 and 18 are respectively enclosed by sheet metal chambers 19 and 20, at the bottoms of which drain holes 21 and 22 are provided to drain off the leakage water. The bottom of the stand is provided with an exhaust hole 23 to be connected to a suitable exhaust pipe. It will be easily understood

from the foregoing, that the fan will be operated when pressure water is supplied from the pipe 13.

Fans of known types are heated by heat due to friction of revolving parts thereof so that all of them are unable to supply air even at its atmospheric state and have a tendency of only supplying somewhat hot and unpleasant air. According to this invention, this drawback is entirely obviated because the motor part of the fan is continuously cooled by water, so that the air is cooled down to atmospheric temperature and very refreshing drafts can be supplied by the new fan even during a long and continued use thereof.

Claim:

A hydraulic fan comprising a hollow stand, the top of which is partly rounded to provide a casing having bearing openings in the opposite sides thereof, a transverse shaft journalled in the openings and projecting beyond the sides of the casing, a turbine on the shaft within the casing and including blades having intermediate angular portions and side arc-shaped portions, a fluid pressure pipe arranged within the casing to direct fluid against the apex of the angular portions of the blades, disks on the projecting ends of the shafts adjacent the openings for preventing water from splashing and leaking through said openings, members forming, with the casing, chambers to enclose the disks and provided with drain holes to drain off leakage water in the hollow stand, brackets secured to the opposite sides of the casing, one of which forms a fan guard, fan blades also on the shaft, the extreme ends of the shaft being provided with recesses, screw threaded pins adjustable in said brackets having pointed ends engaged in said recesses for rotatably supporting the shaft and adapted to move the shaft axially to center the turbine blades in proper position relative to the fluid pressure pipe.

In testimony whereof I affix my signature.

MASA NAGAO.
